UNITED STATES PATENT OFFICE

171,264

ILLUMINATED TWEEZERS

Ulman B. Peterson, Pasadena, and Warren A. Johnson, Arcadia, Calif.

Application September 3, 1953, Serial No. 26,696

Term of patent 7 years

(Cl. D86—10)

To all whom it may concern:

Be it known that we, Ulman B. Peterson and Warren A. Johnson, both citizens of the United States and residents, respectively, of Pasadena and Arcadia, county of Los Angeles, State of California, have invented a new, original, and ornamental Design for Illuminated Tweezers, of which the following is a specification, reference being had to the accompanying drawing, forming part thereof.

Referring to the drawing:

Fig. 1 is a perspective view of illuminated tweezers, showing our new design;

Fig. 2 is a side elevation thereof;

Fig. 3 is a top plan view thereof, and

Fig. 4 is an end elevation as seen from the left of Fig. 3.

We claim:

The ornamental design for illuminated tweezers, as shown.

ULMAN B. PETERSON.
WARREN A. JOHNSON.
